(57) **CLAIM**

The ornamental design for a splitting head, as shown and described.

DESCRIPTION

FIG. 1 is perspective view of a splitting head showing our new design;

FIG. 2 is a side view of the splitting head;

FIG. 3 is top view of the splitting head;

FIG. 4 is bottom view of the splitting head; and,

FIG. 5 is a rear view of the splitting head.

The broken lines illustrate portions of the design that form no part of the claim.
